CYCLOPARAFFIN PRODUCTION

William E. Ross, Berkeley, and Philip Pezzaglia,
Oakland, Calif., assignors to Shell Develop-
ment Company, San Francisco, Calif., a corpo-
ration of Delaware

Application July 17, 1944, Serial No. 545,349

7 Claims. (Cl. 260—666)

1

This invention relates to the production of cycloparaffins of hydroaromatic structure from hydrocarbon mixtures of relatively wide boiling range such as naphthenic gasolines or fractions thereof comprising cycloparaffins of hydroaromatic and non-hydroaromatic structure in admixture with open chain paraffinic hydrocarbons. The invention relates more particularly to an improved process for the more efficient production of cyclohexane from naphthenic gasolines and fractions thereof comprising methylcyclopentane and cyclohexane.

The cycloparaffins of hydroaromatic structure, particularly cyclohexane, are of great value as starting materials and intermediates in the production of a wide variety of organic products. A most fertile source of these highly desirable materials resides in the naturally occurring hydrocarbon mixtures of naphthenic character such as naphthenic, natural and straight run gasolines, etc. Other sources comprise hydrocarbon mixtures of naphthenic character boiling in the gasoline boiling range obtained by fractionation of the products of many of the processes involving the catalytic or thermal treatment of hydrocarbons or carbonaceous materials. As is well known, these readily available hydrocarbons constitute highly complete mixtures of a plurality of individual hydrocarbons, many of which have similar or closely approximating boiling points and many of which are capable of forming azeotropes with one another during distillation. Realization of the full advantages inherent in the many chemical processes relying upon the cycloparaffins of hydroaromatic structure as starting or intermediate materials has been handicapped by the lack of a process enabling efficient production of the cycloparaffins of hydroaromatic structure on a practical scale from these available complex mixtures. Not only is it imperative that such cycloparaffins of hydroaromatic structures be produced with high yields, but it is essential that the product obtained be of a relatively high purity and yet involve the use of a minimum of operative steps.

Efficient production of a cycloparaffin of hydroaromatic structure such as, for example, cyclohexane from a readily available hydrocarbon mixture of naphthenic character involves not only the problem of recovering substantially all 50 of the cyclohexane inherently present in such mixtures, but the simultaneous conversion of the cycloparaffins of non-hydroaromatic structure such as methylcyclopentane to cyclohexane. Separation of either or both of these cycloparaffins from the complex hydrocarbon mixtures in which they are generally encountered, by such methods as fractional distillation, if at all possible, is often rendered so involved and delicate an operation as to render it highly impractical. By the term

2

"hydroaromatic cycloparaffins", as used throughout this specification and appended claims is meant the cycloparaffins having a hexamethylene ring such as, for example, cyclohexane and the alkyl cyclohexanes, to distinguish them from cycloparaffins of non-hydroaromatic structure comprising those having pentamethylene rings such as, for example, methylcyclopentane and other alkyl cyclopentanes.

10 It is an object of the present invention to provide an improved process for the more efficient production of cycloparaffins of hydroaromatic structure from hydrocarbon mixtures of relatively wide boiling range such as naphthenic gasolines or fractions thereof comprising cycloparaffins of hydroaromatic and non-hydroaromatic structure in admixture with open chain paraffin hydrocarbons of substantially the same boiling range.

15 Another object of the invention is the provision of an improved process for the more efficient production of cyclohexane from hydrocarbon mixtures of relatively wide boiling range such as naphthenic gasolines.

20 Still another object of the invention is to provide an improved process for the more efficient production of cyclohexane from naphthenic gasoline fractions comprising methylcyclopentane and cyclohexane in admixture with open chain paraffinic hydrocarbons inseparable therefrom by fractionating means. Other objects and advantages of the invention will become apparent from the following description thereof.

25 In accordance with the process of the invention a hydrocarbon mixture of naphthenic character from any suitable source such as, for example, a naphthenic straight run gasoline is subjected to fractionation to separate therefrom a fraction comprising cycloparaffins of non-hydroaromatic and hydroaromatic structure in admixture with open chain paraffins of substantially the same boiling range. The fraction thus obtained is subjected to isomerizing conditions to effect the conversion of cycloparaffins of non-hydroaromatic structure to cycloparaffins of hydroaromatic structure. The resulting isomerizate is subjected to fractionation to separate therefrom a fraction comprising cycloparaffins of non-hydroaromatic structure which is recycled to the isomerization reactor and a fraction comprising cycloparaffins of hydroaromatic structure in admixture with open chain paraffins of substantially the same boiling range. The fraction comprising cycloparaffins of hydroaromatic structure thus separated from the isomerizate is subjected to controlled thermal cracking conditions to effect the substantially selective cracking of open chain paraffins to lower boiling hydrocarbons readily separable from the cycloparaffins. The resulting products are fractionated to separate a fraction comprising cycloparaffins of hydro-

aromatic structure of high purity. As will be apparent from the following detailed description thereof, the invention enables not only the highly efficient production of cycloparaffins of hydroaromatic structure from natural gasolines on a practical scale, but enables the obtaining of the desired product on a large scale in a greater state of purity.

In order to set forth more fully the nature of the invention it will be described herein in detail in its application to the production of cyclohexane from hydrocarbon mixtures of naphthenic character in the gasoline boiling range, with reference to the attached drawing in which the single figure represents a more or less diagrammatic elevational view of one form of apparatus suitable for executing the process of the invention.

A hydrocarbon mixture of naphthenic character such as, for example, a naphthenic straight run gasoline, is forced through valved line 1 into a feed fractionator 2. Within feed fractionator 2 a fraction comprising methylcyclopentane and cyclohexane is separated and forced through valved line 3 into a conversion zone comprising, for example, reactor 4. The fraction separated in fractionator 2 and passed into reactor 4 is of sufficiently wide boiling range to comprise substantially all of the methylcyclopentane and cyclohexane originally present in the straight run gasoline. A fraction boiling in the range of from about 65° C. to about 85° C. has been found particularly desirable. Such a fraction will unavoidably comprise a number of hydrocarbons other than methylcyclopentane and cyclohexane, such as normal hexane, some benzene, and particularly, branched chain heptanes such as 2,2-dimethylpentane and 2,4-dimethylpentane, inseparable from cyclohexane by fractionating means. Although it is preferred to separate and pass to reactor 4 a fraction boiling in the range of from about 65° C. to about 85° C., a fraction comprising a somewhat wider boiling range may suitably be employed. A naphthenic gasoline fraction comprising methylcyclopentane and cyclohexane from any other source may be separately introduced through valved line 5 into line 3 and may comprise a part or all of the charge to the system.

Within reactor 4 the hydrocarbon fraction is contacted under cycloparaffin isomerizing conditions with an isomerization catalyst. Suitable catalysts comprise those containing a metal halide of the Friedel-Crafts type, particularly those comprising a halide of aluminum such as $AlCl_3$ and/or $AlBr_3$. Particularly suitable catalysts comprise the organo-aluminum halide complexes, preferably a preformed aluminum chloride hydrocarbon complex. Other suitable catalysts comprise those of the molten salt type containing the aluminum halide in admixture with one or more halide salts. The temperature in reactor 4 is maintained in the range of from about 20° C. to about 100° C. and preferably from about 50° C. to about 90° C. The particular temperature chosen within this specified temperature range will be governed to at least a substantial degree by the particular catalyst employed. When utilizing a preformed aluminum halide hydrocarbon complex as the catalyst a temperature in the range of from about 65° C. to about 85° C. is somewhat preferred. A hydrogen halide promoter such as, for example, hydrogen chloride, is introduced into the conversion zone by means of line 1. The hydrogen chloride is added in an amount equal to from about 0.1 to about 3% and preferably from about

5 to about 2% by weight of the hydrocarbon charge to the conversion zone. Higher or lower concentrations of the hydrogen chloride may at times be desirable depending upon variation in operating conditions. Under these conditions methylcyclopentane will be converted to cyclohexane in reactor zone 4.

Effluence from reactor 4 is passed through line 9 into an accumulator 10 and thence through line 11 into a stripping zone 12. In stripping column 12 a vapor fraction comprising the hydrogen chloride promoter is separated and recycled to the conversion zone 4 by means of line 7. Make-up hydrogen chloride is introduced into the system by means of valved line 13. Liquid hydrocarbons are passed from the stripper 12 through line 14 into a separating zone represented in the drawing by the single fractionator 15. Within fractionator 15 there are separated a fraction comprising material lower boiling than cyclohexane and including unconverted methylcyclopentane; a cyclohexane concentrate; and liquid bottoms comprising materials higher boiling than cyclohexane. The fraction comprising methylcyclopentane is removed overhead through line 17 and recycled at least in part to reactor 4 by means of line 18. The stream thus recycled may be subjected to a fractionation to effect the separation of hydrocarbons other than methylcyclopentane therefrom prior to passage to the conversion zone. The cyclohexane concentrate, separated in fractionator 15, boiling, for example, in the range of from about 75° C. to about 85° C. will comprise, besides cyclohexane, some benzene and branched chain heptanes inseparable from cyclohexane by fractionating means. The cyclohexane concentrate is taken from an intermediate part of fractionator 15 and passed through line 20 to a thermal cracking zone. The following example is illustrative of the production of the cyclohexane concentrate in accordance with the process of the invention.

Example I

45 A naphthenic gasoline was fractionated to separate therefrom a fraction boiling in the range of from 65° C. to 85° C. The composition of the fraction thus obtained is given in column A of the following Table I. The hydrocarbon fraction was isomerized by contact with a preformed aluminum chloride-hydrocarbon complex at a temperature of 80° C. with a contact time of 26 minutes. Hydrogen chloride in an amount equal to 1% by weight of the charge was added. The composition of the isomerizate is given in column B of Table I. The isomerizate was fractionally distilled to separate therefrom a cyclohexane concentrate boiling in the range of from 75° C. to 85° C. and a lighter boiling fraction comprising methylcyclopentane for recycling to the isomerization zone. The composition of the cyclohexane concentrate thus obtained is given in column C of Table I.

	A	B Isomerizate	C Cyclohexane concentrate
Boiling range, ° C.	65-85		75-85
Composition, per cent by volume:			
Methylpentanes	2.5	13	
n-Hexane	30	20	
Dimethylpentanes	3	3	7
Methylcyclopentane	37	15	
Cyclohexane	20.5	40	88
Benzene	7	7	5
Higher boiling		2	

It is seen from the foregoing example that the cyclohexane concentrate produced contains only 88% cyclohexane and includes 7% dimethylpentanes difficult to separate therefrom by fractionation or other means. Such a proportion of open chain paraffins is substantially above that tolerated in many of the processes wherein cyclohexane is utilized as starting or intermediate material. Reduction of the open chain paraffin content of such a fraction on a large scale would be so costly as to render the process economically unfeasible. In accordance with the process of the invention, however, the open chain paraffins are separated efficiently resulting in the production of a cyclohexane of high purity in a minimum of operative steps.

The thermal cracking zone to which the cyclohexane concentrate is passed through line 20 may comprise an externally heated elongated coil 23 positioned within a furnace structure 24. Prior to passage into coil 23 the cyclohexane is preferably subjected to a treatment, by means not shown in the drawing, to effect the removal of benzene therefrom. Such treatment may comprise scrubbing with sulfuric acid or a selective solvent for the aromatic hydrocarbon or any other suitable means. The resulting cyclohexane concentrate, substantially free of benzene, but still comprising the open chain paraffins is passed into coil 23.

Within coil 23 the cyclohexane concentrate is subjected to a temperature in the range of from about 500° C. to about 700° C. and preferably from about 550° C. to about 650° C. The stream is preferably maintained in this temperature range for a period of time of from about 5 seconds to about 30 seconds and preferably from about 10 seconds to about 20 seconds. Under these conditions open chain paraffins comprising the open chain heptanes are substantially selectively cracked to lower boiling hydrocarbons readily separable from cyclohexane. From coil 23 the cracked stream is passed through valved line 25 into fractionator 26. A valved line 27 is provided for the introduction of a suitable quenching medium into line 25. Within column 26 there is separated overhead a vapor fraction comprising material lighter boiling than cyclohexane. Bottoms, comprising cyclohexane and a relatively small amount of material higher boiling than cyclohexane, are passed from column 26 through line 29 into fractionator 30. Within column 30 cyclohexane comprising a substantially reduced amount of open chain paraffins boiling at or near the boiling point of cyclohexane is taken as an overhead product through line 32. Products resulting from the cracking of the open chain paraffins will comprise unsaturated hydrocarbons, for example, of olefinic structure. The cyclohexane taken off through line 32 (optionally the entire effluence of the cracking coil 24) is preferably subjected to any suitable olefin removal treatment comprising, for example, scrubbing with a selective solvent or acid as sulfuric acid, by means not shown in the drawing, to assure the removal of unsaturated hydrocarbons therefrom.

In the preferred method of execution of the process of the invention, the hydrocarbon fraction passed to cracking coil 23 will comprise substantially only cycloparaffins of hydroaromatic structure. At least a substantial part of the cycloparaffins of non-hydroaromatic structure present in the isomerize may, however, be included. When operating in this manner the cycloparaffins of non-hydroaromatic structure are

separated from the cracked products as a separate fraction within column 30 and recycled therefrom through line 33 to the isomerization zone.

Example II

The cyclohexane concentrate separated from the isomerize and the composition of which is given in column C of Table I was scrubbed with sulfuric acid to remove the benzene therefrom. The resulting benzene free hydrocarbon mixture was then washed with a dilute caustic solution to remove any acidic constituents therefrom. The resulting cyclohexane concentrate now substantially free of benzene was subjected to selective paraffin cracking at a temperature of 600° C. and a contact time of from 9 to 12 seconds. 43% of the dimethyl pentane present in the charge to the cracking zone was thereby converted to material substantially lower boiling than cyclohexane and readily separable therefrom. Distillation and acid treatment of the products from the cracking zone yielded cyclohexane of better than 95% purity.

It is apparent from the foregoing that the invention provides a highly efficient method for the production of cyclohexane with a minimum of operative steps from readily available hydrocarbon mixtures of naphthenic character comprising methylcyclopentane and cyclohexane; the cyclohexane thus being produced not only with high yields, but in a high state of purity free of any substantial amount of highly undesirable branched chain heptanes generally present in cyclohexanes produced by methods available heretofore.

The above detailed illustrative description of the invention has been directed to the production of cyclohexane. The invention is, however, not limited to the production of only this cycloparaffin of hydroaromatic structure and may be applied with advantage to the production of other cycloparaffins of hydroaromatic structure from complex naphthenic hydrocarbon mixtures. Thus, the process of the invention is applied to the production of methylcyclohexane from a naphthenic gasoline by separation therefrom of a fraction comprising cycloparaffins of non-hydroaromatic and hydroaromatic structure having seven carbon atoms to the molecule, such as dimethylcyclopentane and methylcyclohexane respectively, and the paraffinic hydrocarbons of close boiling range inseparable therefrom by fractionation on a practical scale. The fraction thus obtained is isomerized as described above in isomerization zone 4 and a fraction predominating in cycloparaffins of hydroaromatic structure is separated from the resulting isomerize. The fraction comprising the cycloparaffins of hydroaromatic structure thus obtained and unavoidably comprising open chain paraffins inseparable therefrom by fractionation is subjected to thermal selective paraffin cracking conditions thereby converting the open chain paraffins to lower boiling products readily separable from the cycloparaffins. A cycloparaffin of hydroaromatic structure of high purity and free of any substantial amount of open chain paraffins is separated by fractionation from the cracked product.

For the purpose of simplicity, parts of apparatus such as pumps, separators, condensers, etc., not essential to a complete understanding of the invention have been omitted from the drawing. Similarly fractionating zones depicted in the drawing by single fractionators will in actual practice comprise the use of more than one such

fractionator to effect the indicated separations.

We claim as our invention:

1. Process for the production of cyclohexane from a naphthenic gasoline fraction having a maximum boiling point below the boiling point of normal heptane and comprising methylcyclopentane, cyclohexane and open chain paraffins having six and seven carbon atoms to the molecule, which comprises contacting said fraction with an aluminum halide isomerization catalyst at methylcyclopentane isomerizing conditions, thereby converting methylcyclopentane to cyclohexane, separating a cyclohexane fraction comprising cyclohexane and close boiling open chain paraffins from the resulting isomerizate, subjecting said cyclohexane fraction to thermal cracking conditions at a temperature of from about 550° C. to about 700° C. and for a period of time of from about 5 to about 30 seconds, thereby selectively converting open chain paraffins to lower boiling hydrocarbons, and fractionally distilling hydrocarbons comprising cyclohexane from the cracked products.

2. Process for the production of cyclohexane from a gasoline fraction obtained in the fractionation of naphthenic gasoline and comprising methylcyclopentane, cyclohexane and open chain paraffins of substantially the same boiling range, which comprises contacting said fraction with an isomerization catalyst comprising a metal halide of the Friedel-Crafts type at methylcyclopentane isomerizing conditions, thereby converting methylcyclopentane to cyclohexane, separating a cyclohexane fraction comprising cyclohexane and close boiling open chain paraffins from the resulting isomerizate, subjecting said cyclohexane fraction to thermal selective paraffin cracking conditions at a temperature of from about 550° C. to about 650° C. and for a period of time of from about 5 to about 30 seconds, thereby selectively converting open chain paraffins to lower boiling hydrocarbons, and fractionally distilling hydrocarbons comprising cyclohexane from the cracked products.

3. Process for the production of cyclohexane from a gasoline fraction obtained in the fractionation of naphthenic gasoline and comprising methylcyclopentane, cyclohexane and open chain paraffins of substantially the same boiling range, which comprises contacting said fraction with an aluminum chloride isomerization catalyst at methylcyclopentane isomerizing conditions, thereby converting methylcyclopentane to cyclohexane, subjecting the resulting isomerizate to thermal cracking conditions at a temperature of from about 550° C. to about 650° C. for a period of time from about 10 to 20 seconds, thereby selectively converting open chain paraffins to lower boiling hydrocarbons, fractionally distilling hydrocarbons comprising cyclohexane and hydrocarbons comprising methylcyclopentane from the cracked products, and recycling said hydrocarbons comprising methylcyclopentane to said isomerization step.

4. Process for the production of cyclohexane from a gasoline fraction obtained in the fractionation of naphthenic gasoline and comprising methylcyclopentane, cyclohexane and open chain paraffins of substantially the same boiling range, which comprises contacting said fraction with an aluminum halide isomerization catalyst at methylcyclopentane isomerizing conditions, thereby converting methylcyclopentane to cyclohexane, subjecting the resulting isomerizate to thermal

cracking conditions at a temperature of from about 550° C. to about 650° C. for a period of time of from about 5 to about 30 seconds, thereby selectively converting upon chain paraffins to lower boiling hydrocarbons, fractionally distilling hydrocarbons comprising cyclohexane and hydrocarbons comprising methylcyclopentane from the cracked products, and recycling said hydrocarbons comprising methylcyclopentane to said isomerization step.

5. Process for the production of cyclohexane from a gasoline fraction obtained in the fractionation of naphthenic gasoline and comprising methylcyclopentane, cyclohexane and open chain paraffins of substantially the same boiling range, which comprises contacting said fraction with an isomerization catalyst comprising a metal halide of the Friedel-Crafts type at methylcyclopentane isomerizing conditions, thereby converting methylcyclopentane to cyclohexane, subjecting the resulting isomerizate to thermal cracking conditions at a temperature of from about 550° C. to about 650° C. and for a period of time of from about 5 to about 30 seconds, thereby selectively converting open chain paraffins to lower boiling hydrocarbons, fractionally distilling hydrocarbons comprising cyclohexane and hydrocarbons comprising methylcyclopentane from the cracked products, and recycling said hydrocarbons comprising methylcyclopentane to said isomerization step.

6. Process for the production of cyclohexane from a naphthenic gasoline fraction having a maximum boiling point below the boiling point of normal heptane and comprising methylcyclopentane, cyclohexane and open chain paraffins having six and seven carbon atoms to the molecule, which comprises contacting said fraction with an aluminum halide isomerization catalyst at methylcyclopentane isomerizing conditions, thereby converting methylcyclopentane to cyclohexane, subjecting the resulting isomerizate to thermal cracking conditions at a temperature of from about 550° C. to about 650° C. for a period of time of from about 5 to 30 seconds, thereby selectively converting open chain paraffins to lower boiling hydrocarbons, fractionally distilling hydrocarbons comprising cyclohexane and hydrocarbons comprising methylcyclopentane from the cracked products, and recycling said hydrocarbons comprising methylcyclopentane to said isomerization step.

7. Process for the production of cyclohexane from hydrocarbon mixtures comprising methylcyclopentane, cyclohexane and open chain paraffins of substantially the same boiling range, which comprises contacting said fraction with an aluminum halide isomerization catalyst at methylcyclopentane isomerizing conditions, thereby converting methylcyclopentane to cyclohexane, subjecting the resulting isomerizate to thermal cracking conditions at a temperature of from about 550° C. to about 700° C. and for a period of time of for about 5 to about 30 seconds, thereby selectively converting open chain paraffins to lower boiling hydrocarbons, fractionally distilling hydrocarbons comprising cyclohexane and hydrocarbons comprising methylcyclopentane from the cracked products, and recycling said hydrocarbons comprising methylcyclopentane to said isomerization step.
